Primary Examiner — Kimberly Barnes(74) *Attorney, Agent, or Firm* — Breakwater Law Group(57) **CLAIM**

The ornamental design of a helmet insert, substantially as shown and described.

DESCRIPTION

FIG. 1 is a perspective view of a helmet insert configured in accordance with the present invention;

FIG. 2 is a top view thereof;

FIG. 3 is a bottom view thereof;

FIG. 4 is a left side elevational view thereof, the right side elevational view being a mirror image of the left side elevational view;

FIG. 5 is a front elevational view thereof, the rear elevational view being a mirror image of the front elevational view;

FIG. 6 is a cross-sectional view thereof, taken along Section 6-6 of FIG. 2; and,

FIG. 7 is another cross-sectional view thereof, taken along Section 7-7 of FIG. 2.

1 Claim, 7 Drawing Sheets(56)
